UNITED STATES PATENT OFFICE.

JOHN DONALD DOWNIE, OF AVONMORE, CANADA, ASSIGNOR TO ONTARIO WIND ENGINE AND PUMP COMPANY, LIMITED, OF TORONTO, CANADA, INCORPORATED, A CORPORATION OF ONTARIO.

ADJUSTABLE FOOT-GEAR FOR WINDMILLS.

SPECIFICATION forming part of Letters Patent No. 730,524, dated June 9, 1903.

Application filed June 24, 1902. Serial No. 113,028. (No model.)

To all whom it may concern:

Be it known that I, JOHN DONALD DOWNIE, windmill expert, of the village of Avonmore, in the county of Stormont, in the Province of 5 Ontario, Canada, have invented certain new and useful Improvements in Adjustable Foot-Gear for Windmills, of which the following is a specification.

My invention relates to improvements in 10 foot-gear for windmills; and the object of the invention is to devise a foot-gear for this class of mill which may be located at any desired position on the barn-floor or any suitable out-house or supporting-frame and which will accommodate itself to any position of machine 15 or any one of several which it is desired to drive; and it consists, essentially, of a mast or standard, suitable bearings secured to the same, a vertical shaft journaled in such bearings, a swinging bracket swung on the vertical shaft, a horizontal shaft journaled therein and in a cup formed on a sleeve through which the vertical shaft extends, a bevel-gear 20 being provided on the horizontal shaft and a bevel-gear on the vertical shaft, with which the former meshes, and a quadrant being provided whereby the position of the swinging bracket may be adjusted so as to hold the horizontal shaft in any position to which it 25 may be swung, the parts being arranged and constructed in detail, as hereinafter more particularly explained.

Figure 1 is a perspective view of my improved foot-gear. Fig. 2 is a detail showing 30 the form of quadrant and of the bracket.

In the drawings like letters of reference indicate corresponding parts in each figure.

A is the mast, and B and C are the upper 35 and lower bearings, the lower bearing having formed therewith a quadrant C', provided with a series of holes c. The quadrant C' is provided with gripping-lips c', whereby it is held from vertical displacement on the mast. Both bearings B and C are secured to the mast by 40 suitable bolts.

D is a swinging bracket, through bosses on the ends of which the vertical shaft E extends, such vertical shaft also necessarily extending through the bearings B and C.

D' is a sleeve which is attached to or forms 50 part of the bracket D and is provided with a cup-shaped bearing or recess d.

d² is a lug attached to or forming part of the bracket D and extending laterally from the same over the quadrant C'. 55

F is a bolt extending through a hole c in the quadrant C' and through a hole in the lug d², the bolt being securely held in position by a nut.

G is a horizontal shaft which is journaled 60 in the bearing d³ forming part of the bracket D, and in the cup-bearing d.

H is a driving-pulley.

I is a bevel-pinion on the vertical or drive shaft, which meshes with the bevel-pinion J 65 on the horizontal shaft.

It will now be seen that by removing the bolt the swinging bracket, and consequently the driving-pulley H, may be swung into any position necessary, this of course depending on 70 the position in which the machine to be driven is placed and which is most convenient for such machine. The bolt F may then be inserted and the nut placed thereon, and consequently the horizontal shaft G and the pulley H held in the proper position necessary 75 for driving the machine to which it is intended to apply the power.

What I claim as my invention is—

1. The combination with the mast and bearings and the vertical shaft journaled therein, of a bracket having arms pivoted directly to said vertical shaft, a horizontal shaft journaled in the intermediate portion of the bracket and driving connections between 85 said vertical and horizontal shafts, substantially as described.

2. The combination with the mast and bearings and vertical shaft, of the swinging bracket, the horizontal shaft and bearings 90 therefor on the swinging bracket and a suitable drive from the vertical shaft to the horizontal shaft, a quadrant secured to the mast and means on the swinging bracket for engaging such quadrant at any desired point, so 95 as to hold the horizontal shaft in any position to which it may be adjusted as and for the purpose specified.

3. The combination with the mast and the bearings and vertical shaft, of the swinging bracket swung on the vertical shaft and having the lower end provided with an upwardly-extending sleeve having a cup-shaped bearing extending laterally from same, the horizontal shaft journaled in the bearing on the outer end of the bracket and in the cup-shaped bearing and means for holding the swinging bracket in any position to which it may be swung as and for the purpose specified.
4. The combination with the bearings suitably supported and the vertical shaft suitably journaled therein and the quadrant provided

with holes, of the swinging bracket and the horizontal shaft carried thereby and the drive from the horizontal shaft to the vertical shaft and a lug carried by the swinging bracket, and a bolt designed to extend through holes in the quadrant and the lug and thereby hold the swinging bracket and horizontal shaft in the desired position as and for the purpose specified.

JOHN DONALD DOWNIE.
